UNITED STATES PATENT OFFICE.

WILLARD COMEY, OF WESTBOROUGH, ASSIGNOR TO THE AMERICAN STOP-MOTION COMPANY, OF BOSTON, MASSACHUSETTS.

IMPROVEMENT IN WEFT-STOP MECHANISMS FOR LOOMS.

Specification forming part of Letters Patent No. 146,574, dated January 20, 1874; application filed May 2, 1873.

To all whom it may concern:

Be it known that I, WILLARD COMEY, of Westborough, in the county of Worcester and State of Massachusetts, have invented certain new and useful Improvements in Looms, of which the following is a specification:

My present invention relates to certain improvements in an invention secured to myself and Sidney S. Turner by Letters Patent of the United States dated July 16, 1872, and numbered 129,212, entitled "weft-stop mechanism for looms," the object sought being to so arrange the weft-detector device that it shall be sure in its action to operate upon the belt-shifting device when the weft-thread is absent from the detector either from being broken or from being all off from the bobbin. To secure this action, it is necessary that the threads that have already been beaten up and incorporated in the cloth, and yet extending directly from the selvage to the shuttle, as is the case in all looms of the drop-box order—that is, in looms in which more than one shuttle is used—should be kept away from the detectors. This is accomplished by employing detector-guards, which consist of rods or hooks so arranged as to project above the lay at a certain part of the stroke of the lay, that they will prevent the threads that have been beaten up, and extend from the edge of the cloth to the shuttles in the boxes, from falling back onto the lay; and at another part of the stroke the guards must be withdrawn, so as to allow the thread that has just been beaten up to remain so, and not be pulled back by the guard as it retreats with the lay. These guards may be operated from above or below the lay, and may be varied in form and mode of action. My invention also relates to a device for operating the detector-forks.

Figure 1 is a perspective view of a loom upon which my invention is attached. Fig. 2 is a vertical section through the lay and beam of a loom, and shows my device for operating the weft-detector. Fig. 3 is a plan of a part of the lay, and serves to illustrate the action of the threads in relation to the detectors and the detector-guards.

Let A B represent the frame of an ordinary drop-box loom, all the parts of which, except

the weft-detector and the detector-guard, are in common use, and well known, and need not be described. H H, Fig. 1, are the lay ends or box-casings, and are attached to and move with the lay. H² H² are the shuttle-boxes, which are supported on the rods K K, and are operated by cams in the usual manner. P P are the picker-shafts, which, operating through the arm K³, straps K², and picker-staff H¹, give motion to the shuttle.

The weft-detectors C' B' C' B' and belt-shipping device N are made as shown in Figs. 1 and 2, and are fully described in the Letters Patent above referred to.

The detector-guard F, Fig. 1, consists of a rod, the lower end of which is attached to an arm, F³, on the picker-shaft P, so that each motion of the picker-shaft will cause a vertical motion of the detector-guard F. The function of this guard F is illustrated in Fig. 3, in which C represents the lay; W, the cloth; y, the thread that has been beaten up, and x the thread that is being beaten up, the two threads being connected with their shuttles in the box H, the thread y that has been beaten up being held away from the detector by the guard F.

Fig. 3 represents the position of the cloth, threads, and detector-guard when the lay is at the end of its forward stroke. When the lay retreats, the cloth W remaining stationary, it is necessary that the guard F be withdrawn, so that it may pass back with the lay under the thread x; but when the lay again advances the guard F comes into position, and pushes back the thread x, which has become, in its turn, a beaten-up thread.

In Fig. 2, I show my method of operating the detector-forks. C' C'' represent the detector-forks, which are pivoted on a rod, D', extending along the back of the lay, so as to connect the two detectors, one of which is located at each end of the lay, Fig. 1. To the rod D', Fig. 2, I attach a lappet, D'', upon which the bent lever E¹ acts. Thus, when the lever is thrown up, it forces up the lappet and causes the rod to revolve, which throws up the detector-forks C' C'', and when the lever falls the detector-forks fall. The lever E¹ is operated by the cam-piece G' G'', which, being attached to the breast-beam R, is stationary, and

acts on the roller E³ to throw up the lever E¹ as the lay moves over it.

I claim as my invention—

1. In connection with the mechanism of a loom, the combination of the detector-guard F, arm F³, and picker-shaft P, constructed and arranged as described.

2. The combination of the rod D', having at its ends the detectors C' C' and the lappet

D'', with the bent lever E', pivoted as shown, arm G' G'', and breast-beam R, constructed and arranged as described, and for the purpose set forth.

WILLARD COMEY.
